UNITED STATES PATENT OFFICE.

LAWRENCE V. HARE, OF JERSEY CITY, NEW JERSEY, ASSIGNOR TO CONTINENTAL CAN COMPANY, INC., OF SYRACUSE, NEW YORK, A CORPORATION OF NEW YORK.

AIR PUMP FOR SPRAYING DEVICES.

Application filed October 13, 1926. Serial No. 141,361.

The invention relates to new and useful improvements in spraying devices, and more particularly to a spraying device having a cylinder in which a reciprocating piston 5 places air under pressure to be directed across the spray nozzle.

An object of the invention is to provide a spraying device of the above type wherein the cylinder is closed at the end through 10 which the piston rod extends by a metallic head with which is associated a non-metallic member which operates to prevent any drum head noises incident to the movement of the piston rod through a guiding opening in said 15 head.

A further object of the invention is to provide a spraying device of the above type wherein the metallic head is provided with a flanged portion adapted to extend inside of 20 the cylinder, and with a shoulder adapted to engage the end of the cylinder, and wherein said flange is formed with an annular groove into which the wall of the cylinder may be indented for holding the head in engagement 25 with the cylinder.

In the drawings—

Figure 1 is a side view of a spraying device embodying the improvements, and

Fig. 2 is an enlarged sectional view through 30 a portion of the cylinder showing the closing head construction for the cylinder.

Prior to my invention, it has been common to provide a spraying device which includes a chamber in which a liquid to be sprayed is 35 placed, and a nozzle projecting from said chamber, and also a cylinder in which there is a reciprocating piston for directing an air jet across the nozzle to spray the liquid. In devices of this type, there is a reciprocating 40 piston in the cylinder, and a rod with a handle attached for moving the piston. A head is provided at the outer end of the cylinder which has the opening therethrough for the piston rod. These heads have usually been 45 made of wood. The present invention is directed to a metallic head which may be used in place of these wooden heads. This metallic head is preferably formed from sheet metal and includes a portion extending across 50 the open end of the cylinder for closing the same, which has an opening therethrough for the rod. The head also has a flange which is of such size as to fit within the cylinder. The head also has a shoulder adapted 55 to bear against the end of the cylinder. The

flange is provided with an annular groove so that the wall of the cylinder may be indented to hold the head in the cylinder. In order to prevent drum head noises incident to the vibration of the portion of the head which 60 extends across the end of the cylinder, by reason of the movement of the rod through the opening in the head, I have provided a non-metallic member which is attached to the head, preferably to the inside thereof, and 65 extends all the way across the end of the cylinder. This non-metallic member is preferably made of pasteboard, and it is secured to the head by an eyelet.

Referring more in detail to the drawing, 70 my improved spraying device consists of a cylindrical chamber 1 having a filling opening closed by a screw cap 2. This chamber 1 is also provided with a pipe or nozzle 3 which leads down into the chamber. Attached to this chambered portion 1 is a bracket 4 carrying a cylinder 5. The cylinder 5 is provided with the usual opening adjacent the end of the pipe 3. In the cylinder 5 is a piston 6 carried by a piston rod 7. When 75 this piston is reciprocated, air is compressed in the cylinder, and as it escapes through the opening adjacent the end of the pipe 3, the liquid is drawn from the chamber 1 and is ejected in the form of a spray. These parts 80 of the spraying device are well known in the art, and further description thereof is not thought necessary.

The end of the cylinder 5 is closed by a head 8. This head 8 is preferably formed of sheet 90 metal and includes a body portion 9 of disk shape, which is formed with a flange 10. The flange 10 at its inner end is rolled in at 11 so that the flanged portion of the head may be readily inserted in the cylinder for closing 95 the end thereof. This flanged portion is of substantially the same diameter as the inner diameter of the cylinder. The flanged portion 10 is provided with an annular groove 12. The cylinder 5 is preferably made of sheet metal and can be readily, therefore, indented as indicated at 13. The indentations may be made at a series of points about the cylinder, and the indentations will extend into the annular groove in the head, and thus firmly hold the head in the cylinder. On the inside of the head, and flat against the body portion 9 thereof, is a non-metallic member 14. This non-metallic member 14 is clamped to the head by an eyelet 15 which extends 100

through the head and is turned against the outer face of the head and the inner face of the non-metallic member. The piston rod 7 passes through this eyelet.

5 The opening in the metallic head for the piston rod is a guiding opening, and without the non-metallic member, the rod engaging the edge of the metal at the opening through which it passes, is likely to cause a vibration 10 in the body portion 9, thus making drum head noises which are objectionable. By placing this non-metallic member, which is preferably of pasteboard, against the inner face of the head and securing it thereto, all 15 of these noises are avoided. The piston rod 7 is provided with the usual handle 16.

It will be obvious that instead of using an eyelet for securing the non-metallic member to the head, this non-metallic member may 20 be glued to the head in part, or throughout the entire extent thereof. It is also obvious that other ways of securing the non-metallic member to the head may be used without departing from the spirit of the invention as 25 set forth in the appended claims.

Having thus described the invention, what I claim as new and desire to secure by Letters Patent, is—

1. An air pump for a spraying device comprising a cylinder, a piston in said cylinder, a piston rod connected to said piston and a head for closing said cylinder, said cylinder being formed of sheet metal and said head being formed of sheet metal and including a body portion extending across the end of the cylinder and having an inwardly projecting flange adapted to fit within the cylinder, said flange having an annular groove therein into which the cylinder wall may be extended 30 for holding the head in the cylinder.

2. An air pump for a spraying device comprising a cylinder, a piston in said cylinder, a piston rod connected to said piston and a head for closing said cylinder, said cylinder being formed of sheet metal and said head being formed of sheet metal and including a

body portion extending across the end of the cylinder and having an inwardly projecting flange adapted to fit within the cylinder, said flange having an annular groove therein into 50 which the cylinder wall may be extended for holding the head in the cylinder, said head having a shoulder at the outer edge of the body portion for engaging the end of the cylinder. 55

3. An air pump for a spraying device comprising a cylinder, a piston in said cylinder, a piston rod connected to said piston and a head for closing said cylinder, said cylinder being formed of sheet metal and said head being formed of sheet metal and including a body portion extending across the end of the cylinder and having an inwardly projecting flange adapted to fit within the cylinder, said flange having an annular groove therein 60 into which the cylinder wall may be extended for holding the head in the cylinder, said head having a shoulder at the outer edge of the body portion for engaging the end of the cylinder, a non-metallic disk located on the inner face of said head, said disk and head having an opening therethrough for the piston rod, and an eyelet located in said opening and clamping said disk against the head, said non-metallic disk being of substantially the 65 same diameter as the inner diameter of the cylinder. 70

4. An air pump for a spraying device including a cylinder, a piston in said cylinder, a piston rod connected to said piston, a head for closing said cylinder, said head being formed of sheet metal and having an opening centrally therethrough for the piston rod, a non-metallic member disposed at one face of 80 said head and in contact therewith and having an opening centrally therethrough for said piston, and means for securing said non-metallic member to said head centrally of the head for preventing drum head noises therefrom. 85

In testimony whereof, I affix my signature.

LAWRENCE V. HARE.
